UNITED STATES PATENT OFFICE.

CLAUD D. CURRY, OF MEMPHIS, TENNESSEE.

PAPER-ASSOCIATING MACHINE.

1,155,894.

Specification of Letters Patent.

Patented Oct. 5, 1915.

Application filed August 24, 1910. Serial No. 578,714.

To all whom it may concern:

Be it known that I, CLAUD D. CURRY, of Memphis, in the county of Shelby and State of Tennessee, have invented certain new and useful Improvements in Paper-Associating Machines; and I do hereby declare the following to be a full, clear, and exact description of the invention, such as will enable others skilled in the art to which it appertains to make and use the same.

This invention relates to improvements in feeding mechanism for paper associating machines,—the object of the invention being to provide simple and efficient means for withdrawing newspaper sections or collections of sheets from magazines containing the same and properly and accurately conducting them to opening and stuffing mechanism.

With this object in view the invention consists in certain novel features of construction and combinations of parts as herein-after set forth and pointed out in the claims.

In the accompanying drawings: Figure 1 is a longitudinal sectional view of a machine embodying my improvements; Fig. 2 is an enlarged view illustrating the feeding mechanism; Figs. 3 and 4 are enlarged detail views showing portions of the feeding mechanism; Fig. 5 is an enlarged view showing one of the cylinders and needle-box-withdrawing devices which coöperate therewith; Fig. 6 is a sectional view through one of the feed cylinders; Fig. 7 is an enlarged sectional view through one unit of the feeding mechanism; Fig. 8 is a plan view partly in section showing the bottom of a magazine and feeding mechanism below the same, and Figs. 9, 10, 11, 12, 13, 14 and 15 are detail views illustrating the needle box withdrawing devices of the feeding mechanism.

1 represents a framework, in the upper portion of which a plurality of hoppers or magazines 2, 3, 4, are located, each in an inclined position as clearly shown in Figs. 1 and 2. In constructing each magazine, I provide transverse beams 4^a rigid with the framework, and from these beams, brackets 5 project and support shafts 6. Two inclined uprights 7 are adjustably secured near their upper and lower ends to the shafts 6 near respective ends of the latter, as most clearly shown in Figs. 2, 7 and 8. Inclined uprights 8 are spaced from the uprights 7 and are secured to horizontal shafts 9 adjustably mounted in the framework, as

shown in Fig. 8 to enable adjustment of the standards 8. It is apparent that by adjusting the uprights 7 on the shafts 6 and by moving the shafts 9 longitudinally to adjust the positions of the standards 8, the magazine can be adapted for paper sections of different sizes. A bottom plate 10 is disposed below the standards 8 and provided with grooves 11 to receive lugs 12 depending from said standards to guide the latter and maintain them in proper position, and said bottom plate is supported by means of rods 13 mounted in the framework as shown in Fig. 8. Inclined supporting arms 14 for the folded edges of the paper sections, are secured to the shafts 6 intermediate of the uprights 7, and also located between said uprights and in proximity to the supporting arms 14, are vertically movable arms 15, each having a lip 16 at its lower edge to project under the pile of paper sections. The arms 15 are provided with slides 17 movable in guides 18 on the beams 4^a, and these arms are reciprocated vertically for a purpose hereinafter explained, by means of a cam 19,—motion being imparted by said cam, through the medium of an arm 20 (Fig. 7) to a shaft 21 and from this shaft, motion is transmitted to the arms 15 for reciprocating them, by means of arms 22.

Beneath each magazine, a cylinder 23 is located and carried by a shaft 24, suitable gearing being provided for actuating said shaft to rotate the cylinder. Each cylinder 23 comprises a plurality of alined members spaced apart as shown in Figs. 4 and 6 to form peripheral openings 25 and the several members composing the cylinder are made of such length (circumferentially) as to leave large openings 25, at one edge of each of which, rounded flanges or enlargements 27 are formed.

A shaft 28 is located in rear of each cylinder, and on this shaft, arms 29 are hung. These arms enter the cylinder through the openings 25 and their free ends 30 project upwardly so as to terminate above the plane of the cylinder and near the bottom of the adjacent magazine. At the upper end of the curved portion 30 of each arm 29, a needle box construction or withdrawing mechanism for removing the paper sections from the bottom of the adjacent magazine, is located, and this mechanism will now be explained. On the upper end of each arm 29, a head 31 is pivotally supported at 32,—

each of said heads being made with an inclined face 33 which normally lies coincident with the bottom of the magazine and supports the pile of paper sections near one edge (the folded edge) of the same. Each head 31 is made in its under side with recesses 34 (Figs. 9 and 10) for the accommodation of needle bars 35 having grooves 36 to receive guide strips 37 secured in the recesses 34 of head 31. Needles 38 are adjustably secured to the needle bar and project forwardly through holes 39 in the head 31, the inclined face of the latter being notched as at 40 to permit the needles to engage a paper section when they are thrust forwardly. Directly under each head 31 and engaging the same, a sliding plate 41 is located and sustained by guides 42 secured to said head. This plate is made with a plurality of diagonal slots 43 and into these slots, rollers 44, carried by the needle bars, project so that when the plate 41 is moved in one direction, the needles will be projected to engage a paper section and withdrawn when the plate 41 is moved in the reverse direction. Each reciprocating plate 41 has secured thereto, near its respective ends, arms 45 which depend into the cylinder 23 and are provided at their lower ends with socket pieces 46 in which balls 47 are located so as to be in position to be engaged by ribs or shoes 48 located within the cylinder 23. Thus it will be seen that during one portion of the rotation of the cylinder, the ball 47 on one of the arms 45 will be engaged by a rib or shoe 48 so as to move the plate 41 in a direction to project the needles, and that during another portion of the rotation of the cylinder, another rib 48 will engage the ball 47 on the other arm 45 in a manner to move the plate 41 in the reverse direction and withdraw the needles.

Each pivoted head 31 is provided with a bifurcated arm 49 for the reception of a pin 50 on one arm of a lever 51 pivoted between its ends to the upwardly curved portion 30 of the arm 29, the lower end of said lever being pivotally connected with one end of a reciprocating rod 52 by means of a coupling 53. The rod 52 is carried by the arm 29 and is provided at its rear end with a roller 54 entering a cam 55 secured to and driven by the shaft 28. It is apparent that during the rotation of the cam 55, the rod 52 will be reciprocated to oscillate the lever 51, and that when the latter is moved in one direction, the head 31 of the needle box construction will be turned and moved in a direction away from the bottom of the pile of paper sections in the magazine (pulling the edge of the bottom paper section down by the action of the needles)--the reverse movement of said lever 51 serving to restore said head 31 to the position shown in Fig. 10.

65 During the operation of the mechanism

to withdraw a paper section from the magazine, the pivoted head of the needle box structure is not only swung back as above explained, but the whole of this structure is moved down within the cylinder. To accomplish this and to subsequently return the parts to normal positions, I provide cams 56 (Fig. 6) within the cylinder 23 to receive a pin or roller 57 on the curved portion 30 of the arm 29. Thus it will be seen that during one portion of the rotation of the cylinder 23, the pin or roller 57, riding in the cam 56, will cause the arm 29 to be depressed and the needle box structure to move into the cylinder, carrying with it the edge of a paper section to a position to be acted upon by the cylinder.

During the operation of the mechanism above described, the needles will be first projected so as to engage the bottom paper section in the magazine near the folded edge of said paper section. The hinged head 31 will then be dropped and the edge of the paper section pulled down or withdrawn. During the downward movement of the head 31 and the edge of the paper section, the vertically movable arms 15 will also descend (thus permitting the proper descent of the edge of the paper section) and when the edge of the paper section shall have been withdrawn as above explained, the arms 15 will promptly ascend and raise the superimposed paper sections to their normal positions and preventing any superimposed paper section from prematurely escaping from the magazine. When the folded edge of a paper section shall have been withdrawn from the magazine by the dropping of the head 31 while the needles are in engagement with the paper section, the needles will be withdrawn, and then the needle box or withdrawing mechanism will drop into the cylinder and will be followed by the paper section. The folded edge of the paper section is now projecting into the cylinder and, as the latter continues to rotate, one of the flanges or noses 27 will engage said paper section so as to reverse its position and force its folded edge between friction feeding surfaces afforded by a feed roller 58 and a portion of the peripheral face of the cylinder, causing the reversed paper section to be bodily removed from the magazine and fed forwardly. While a paper section is being thus reversed, bodily removed from the magazine and fed forwardly, the needle box devices will be operating to withdraw the edge portion of the next paper section in the magazine so that this paper shall be in position to be engaged by the approaching flange or enlargement 27 on the cylinder for effecting the reversing, withdrawing and feeding of the same as before explained. The withdrawn paper section passes between the roller 58 and the cylinder and is fed

forwardly under a second feed roller 59. The feed rollers 58-59 are mounted in arms 60 pivoted at 60^a and at or near their ends bear against rings 61 at respective ends of the cylinder 23. The feed rollers are yieldingly pressed toward the cylinder by means of spring-pressed rods 62 connected with the pivoted arms 60 and said feed rollers are positively driven by means of suitable gearing 63 as shown in Fig. 5.

The paper section is delivered by the feed rollers to suitably disposed feeding tapes which deliver it between rollers 64-65 to the stuffing mechanism presently to be described. The roller 64 is positively driven by means of suitable gearing and is carried by a pivoted arm 66 with which a rod 67 is connected. This rod passes through a boss 68 and between this boss and an adjustable nut 69, a spring 70 is located. By means of these devices the throat 71 formed between the rollers 64-65 and the pressure of the rollers against the paper can be adjusted.

Below the first and second feeding mechanism, opening and stuffing mechanism for paper sections is located, but as this mechanism constitutes the subject-matter of the invention claimed in another application for patent field by me on even date herewith and designated by Ser. No. 578713, a detail description herein is unnecessary.

Three feeding mechanisms are shown in Fig. 1 of the drawings, and they are all the same in construction and operation; Fig. 1 of the drawing also shows two opening and stuffing mechanisms, which are the same in construction and operation, and they may, for convenience, be designated by the reference characters, A and B. The magazine 2 is intended to contain outer paper sections and the magazines 3 and 4 are to contain "inserts". The first or bottom outer paper section from the magazine 2 will be fed downwardly and will be guided by suitably arranged feed belts as shown in Fig. 1, to the first throat 71 and from the latter to the opening and stuffing mechanism A, where it will be opened as before explained for the reception of "inserts". These "inserts" will be guided by suitably arranged belts as shown in Fig. 1, from the feeding mechanism under the magazines 3 and 4 to the throat 71 over the stuffing mechanism A, and dropped (side by side) between the members of the opened or spread paper section therein, after which the whole will be discharged through the chute 74. The next outer paper section fed from the first magazine will follow the route of the preceding one, until it reaches the throat 71. At this point, the said second outer paper section from the magazine 2 will be diverted by means of a switch 155, and will be conveyed by suitably arranged feeding tapes as shown

in Fig. 1 and deposited into the opening and stuffing mechanism B. The next two inserts from the magazines 3 and 4 will also be diverted by a switch 156 and caused to drop (side by side) between the opened 70 or spread member of the outer paper section in the opening and stuffing mechanism B.

The switch 155 is provided with an arm 157 and this arm is connected with one arm of a bell crank 158. The other arm of the 75 bell crank is provided with a roller 159 which cooperates with a cam 160 on the cylinder 23 of the first feeding mechanism. It will be observed that the cylinder of each feeding mechanism is constructed with two 80 enlargements 27 which are disposed diametrically opposite each other, and that during a complete rotation of the cylinder, two paper sections will be withdrawn from the superimposed magazine and delivered to 85 the feeding tapes. The cam 160 on the cylinder is therefore so shaped that the switch 155 will be operated in a manner to direct one of the paper sections fed during one rotation of the cylinder to the opening and 90 stuffing mechanism A, and so that said switch will direct the other paper section fed forward during the same rotation of the cylinder, to the opening and stuffing mechanism B. The cylinder of the second feeding mechanism is also provided with a cam which actuates a bell crank 161 (Fig. 1) connected with the switch 156 for operating the latter to direct the "inserts" alternately into the opening and stuffing mechanisms 95 A and B.

If a single opening or stuffing mechanism were employed, the paper sections would be run in so close together that said mechanism could not properly operate, and would 105 assemble one paper before another paper section would arrive. By providing two opening or stuffing mechanisms, and feeding the paper sections alternately to these mechanisms as previously explained: double the 110 space is afforded to open one section and insert another, than could be had if but a single mechanism were employed. Furthermore, the construction and operation of the machine as previously explained, permits 115 the paper sections to run at one-half the velocity than that which would be attained if a single opening or stuffing mechanism were employed.

The discharge chutes 74 from the two 120 opening and stuffing mechanisms deliver the stuffed papers to conveyer belts 162 which carry the stuffed papers rearward and then upward and discharge them at 163, onto a conveyer 164, onto which they are properly 125 directed by a feed reel 165.

Having fully described my invention, what I claim as new and desire to secure by Letters-Patent, is:—

1. In a machine of the character described, 130

the combination with a magazine for superimposed paper sections, of a revolute cylinder below the same provided with an engaging flange for a paper section, a swinging arm, a needle box carried by said arm, means for operating the needle box to cause the needles thereof to engage a paper section, means for operating the swinging arm to move the needle box into the cylinder for deflecting the leading edges of the paper section in the path of the engaging flange of the cylinder, and a feed roller adjacent to and coöperating with said cylinder to bodily withdraw a paper section from the magazine.

2. In a machine of the character set forth, the combination of a paper support for superimposed paper sections, a frictional feeding member beneath said support, a carrier moving in a continuous path adjacent said support, a plurality of frictional feeding surfaces on said carrier spaced apart in the direction of travel thereof adapted to successively coöperate with said feeding member during each cycle of movement of the carrier, and means for partially deflecting a plurality of paper sections one by one from the support and presenting the same successively to the action of the feeding member and surfaces during each cycle of the carrier.

3. In a machine of the character described, the combination with a magazine for superimposed paper sections, and a feeding cylinder disposed below the magazine and provided with a flange for engaging paper sections, of a swinging arm projecting between the cylinder and magazine, withdrawing devices for a paper section carried by said arm, means for operating said withdrawing devices and means for swinging said arm, whereby a portion of a paper section will be deflected from the magazine and presented to the engaging flange of the feeding cylinder.

4. In a machine of the character described, the combination with a magazine for superimposed paper sections, and a feeding cylinder mounted below the same and provided with a flange for engaging paper sections, of a swinging arm projecting between said cylinder and magazine, a head pivoted to said arm, means for rocking said head, a needle carrier supported by said head, needles secured to said carrier, means for reciprocating said needle carrier on the head to cause the needle to engage a paper section, and means for swinging said arm to deflect a paper section and present the same to the feeding cylinder.

5. In a machine of the character described, the combination with a support for paper sections, of deflecting means comprising a pivoted head, means for moving said head bodily away from and toward said

support, means for turning said head on its pivotal support, needles carried by said head, and means for reciprocating said needles.

6. In a machine of the character described, the combination with a support for paper sections, of deflecting means for said paper sections, said deflecting means comprising a swinging arm, means for swinging said arm, a head pivoted to said arm, means for turning said head on its pivotal support, a needle carrier mounted on said head, needles secured to said head and adapted to project beyond the face of said head, and means for reciprocating said needle carrier. 70

7. In a machine of the character described, the combination with a support for paper sections, of deflecting means for the paper sections, said deflecting means comprising a swinging arm, means for swinging said arm, a head pivotally supported by said arm, a needle carrier supported by said head, needles secured to said carrier and adapted to project beyond the face of the head, means for reciprocating the needle carrier, an arm projecting from said head, a lever pivoted to the swinging arm and connected with the arm on the pivoted head, a cam, and a rod mounted on said swinging arm and coöperating at one end with 85 said cam, the other end of said rod being connected with the pivoted lever on the swinging arm.

8. In a machine of the character described, the combination with a support for paper sections, of deflecting means for the paper sections, said deflecting means comprising an arm mounted to swing, a rotary cam coöperating with said arm to swing the same, a pivoted head carried by said arm, a needle carrier on said head, needles secured to said carrier and adapted to project beyond the face of said head, a pivoted lever supported by the swinging arm and connected with the pivoted head, a rod mounted 100 on the swinging arm and connected at one end to said pivoted lever, a cam for reciprocating said rod, and means for reciprocating the needle carrier. 105

9. In a machine of the character described, the combination with a support for paper sections, of deflecting means for the paper sections, said deflecting means comprising a head having perforations, means for moving said head away from and toward 115 said support, a reciprocating needle carrier supported by said head, needles secured to said carrier and projecting through the perforations of the head, a reciprocating plate carried by the head and provided with diagonal slots, pins on the needle carrier and entering said diagonal slots, and means for reciprocating said plate. 120

10. In a machine of the character described, the combination with a support for 130

paper sections, and a feeding cylinder disposed below the same, of deflecting means between said support and feeding cylinder for moving paper sections from said support 5 to the feeding cylinder, said deflecting means comprising an arm mounted to swing, a cam carried by the cylinder and co-operating with said arm to swing the same, a head on said arm, a reciprocating needle 10 carrier supported by said head, needles secured to said carrier and adapted to project beyond the head, and means for reciprocating the needle carrier.

11. In a machine of the character described, the combination with a support for 15 paper sections, and a feeding cylinder disposed below the same, of deflecting means between the support and cylinder for moving paper sections from said support to the 20 feeding cylinder, said deflecting means comprising a head between the support and cylinder, means for supporting and moving said head, a reciprocating needle carrier supported by said head, needles secured to said 25 carrier and adapted to project beyond the head, a plate mounted on said head and having diagonal slots, pins projecting from the needle carrier and entering the slots in said plate, arms projecting from said plate and 30 devices in the cylinder and co-operating with said arms to reciprocate said plate to reciprocate the needle carrier.

12. In a machine of the character described, the combination with a support for 35 paper sections, and a feeding cylinder below the same, of deflecting means for moving paper sections and presenting the same to the feeding cylinder, said deflecting means comprising a swinging arm adapted to 40 enter said cylinder, a cam in the cylinder and co-operating with said arm to swing the same, a head pivotally supported by said arm, means for rocking said head, a needle carrier supported by the head, needles secured to said carrier and projecting beyond 45 the head, an operating plate carried by the head for reciprocating the needle carrier, arms depending from said plate, and projections in the feeding cylinder co-operating 50 with said arms for reciprocating the needle carrier operating plate.

13. In a machine of the character described, the combination with a support for paper sections, of a feeding cylinder provided with a peripheral opening and with an engaging flange for paper sections, a swinging arm entering the peripheral opening of the cylinder, withdrawing devices for a paper section carried by said arm for deflecting a paper section from its support and presenting the deflected part to the engaging flange of the cylinder, mechanism for

operating the withdrawing devices, and a feed roller co-operating with said cylinder.

14. In a machine of the character described, the combination with a support for paper sections, of a feeding cylinder below the same, said cylinder having openings and provided at one edge of each opening with an engaging flange for paper sections, a feed roller co-operating with said cylinder, a swinging arm disposed to enter the cylinder, and paper section engaging and deflecting means carried by said arm for partially deflecting paper sections from the support and presenting the deflected part to the engaging flange of the feeding cylinder.

15. In a machine of the character described, the combination with a support for paper sections, of a feeding cylinder below the same and having an opening and a paper engaging flange, deflecting devices between cylinder and said support and adapted to enter the opening of said cylinder, means for operating said deflecting devices to partly deflect a paper section from said support and dispose the deflected part within the cylinder in position to be engaged by the flange of the latter, and a feed roller co-operating with said cylinder.

16. In a machine of the character described, the combination with a support for paper sections, of a feeding cylinder comprising a plurality of spaced sections forming peripheral openings, said sections cut away forming longitudinal openings and an engaging flange at one end of each of said last mentioned openings, swinging arms projecting through the peripheral openings of the cylinder, deflecting devices carried by said swinging arm to partly deflect a paper section from its support and carry the deflected part into the cylinder in position to be engaged by a flange thereof, and a feed roller co-operating with said cylinder.

17. In a machine of the character described, the combination of a magazine comprising adjustable members, a feeding cylinder under the magazine and provided with a paper engaging part to reverse the leading end of the paper, a feed roller co-operating with said cylinder, and means for partly deflecting a paper section downwardly from the magazine and presenting the deflected part to the engaging means of the feeding cylinder.

In testimony whereof, I have signed this specification in the presence of two subscribing witnesses.

CLAUDE D. CURRY.
